UNITED STATES PATENT OFFICE.

JOHN SCHULDE, OF ST. LOUIS, MISSOURI, ASSIGNOR TO HARRY L. HUSSMAN
REFRIGERATOR & SUPPLY COMPANY, OF ST. LOUIS, MISSOURI, A CORPORA-
TION OF MISSOURI.

REFRIGERATOR.

Application filed June 11, 1917. Serial No. 174,072.

To all whom it may concern:

Be it known that I, JOHN SCHULDE, a citizen of the United States, and residing at St. Louis, in the State of Missouri, have invented the certain new and useful Improvement 5 in Refrigerators, of which the following is a specification.

This invention relates to show-case refrigerators, being directed more particularly to 10 features in the nature of improvements on a refrigerator of this type disclosed in Patent Number 1,225,682, granted May 8, 1917.

In the operation of such refrigerators, it 15 is of the highest importance that a circulation of air be maintained through the show-case and that the air in circulation be caused to travel in an outgoing path from the refrigerant along the bottom of the show-case and in a return path to the refrigerant along 20 the top of the show-case, whereby the cold or refrigerated air travels along beneath the display shelves and upward through the goods thereon, and the warm air passes above the goods back to the refrigerant. It 25 is also desirable that the waste from the refrigerant be utilized as an auxiliary cooling medium in the show-case and that dead air spaces or pockets, which create eddy currents in the air circulating through the show-case, 30 be avoided.

It has been found that in the use of refrigerators of this type, there exists a tendency to pile and arrange the goods on the display shelves in such a manner that the 35 circulation of air through the show-case, and particularly the return passage of the air at the top of the case, is seriously affected even to the extent, at times, of being entirely shut off.

40 This invention has among its objects, therefore, to effectually provide against interference with the circulation of the air through the show-case and to insure a free return passage of the warm air above the goods to the refrigerant.

45 A further object of the invention is to provide against the formation of dead air spaces or pockets, particularly at the ends and corners of the case, thus to insure proper circulation of the air and its freedom from eddy current.

50 Further objects of the invention are to generally improve and simplify the construc-

tion and operation of a refrigerator of the type in question.

55

With the above and other objects in view, the invention comprises the novel features of construction and combination of parts more fully hereinafter described.

It is proposed to employ as a refrigerant, 60 a mixture of cracked ice and salt, because of the known properties of such a mixture to produce, with a minimum quantity of ice, a maximum degree of refrigeration, that is, a maximum lowering of temperature, comparative with the amount of ice used.

In the accompanying drawings,

Figure 1 is a side elevation of a show-case refrigerator embodying the invention;

Figure 2 is a vertical section taken centrally and longitudinally therethrough;

Figure 3 is a cross section taken on the line 3—3, of Fig. 2, and showing parts on an enlarged scale; and,

Figure 4 is a similar view taken on the line 4—4 of Fig. 2.

Referring to the drawings, it will be seen that the refrigerator comprises an oblong box or casing 1 having suitably insulated walls and enlarged at one end, herein termed the rear end, to provide a refrigerating compartment 2 which opens into the show-case proper forming the refrigerator compartment 3.

Set in the casing 1 in position to form the top wall of the compartment 2 is a hinged lid or door 4, while set in the front side wall of the show-case proper is a pair of fixed transparent panels 5, and in the rear wall thereof, a plurality of transparent panels 6 hinged as shown, to form doors affording ready access to the interior of the compartment 3 which is adapted to receive the goods to be displayed. At this point it will be noted that the side walls of the casing slope from the top thereof downward and outward to a point below the panels 5 and 6, as seen more clearly in Fig. 4, whereby the goods on display may be conveniently viewed through these transparent sides of the case.

80

Set in the casing 1 in position to form the 85 top wall of the compartment 2 is a hinged lid or door 4, while set in the front side wall of the show-case proper is a pair of fixed transparent panels 5, and in the rear wall thereof, a plurality of transparent panels 6 hinged as shown, to form doors affording ready access to the interior of the compartment 3 which is adapted to receive the goods to be displayed. At this point it will be noted that the side walls of the casing slope from the top thereof downward and outward to a point below the panels 5 and 6, as seen more clearly in Fig. 4, whereby the goods on display may be conveniently viewed through these transparent sides of the case.

90

Suitably sustained in the refrigerating compartment 2, to which access may be had through the door 4, is a container 7 preferably composed of sheet metal and traversed fore and aft by a plurality of tubular flues 105 8 and 9, constituting air passages opening

at one end through the front wall of the container toward the compartment 3 and at the other end into an air space or chamber 10, suitably formed at the rear end of the container and made common to all of the flues or passages. This container is adapted to receive the refrigerant in the form of a mixture of salt and ice, and under the construction set forth, there is imparted to the refrigerating body or unit, comprising the container and its contained refrigerant, a maximum surface area for a given cubic space. In consequence, there is offered to the air which may circulate freely over and through this body, a relatively large refrigerating surface resulting in a rapid absorption of heat from the air and, therefore, in a rapid and thorough refrigeration of the latter. The passages or flues 8 and 9 are all pitched at a suitable inclination from their rear ends downwardly and the passages 8 are tapered from end to end with their larger ends opening toward the compartment 3, all for a purpose which will more fully hereinafter appear.

The bottom of the container is made up of a plurality of spaced channelled bars or slats 11, arranged, as seen more clearly in Figure 3, below the spaces between the lower flues 8 and with sharply convex faces of the slats uppermost. These slats cooperate with the flues to support the refrigerant mixture in the container and at the same time permit free escape of the water wasting from said refrigerant as the ice melts.

Arranged in the compartment 2 beneath the container 7, is a drip pan 12 subdivided by a vertical fore and aft partition 13 into a pair of compartments, and adapted to overflow at its forward edge into a pair of overflow pans 14 adapted, one to each of the compartments of the drip pan and extending therefrom longitudinally through the show-case or refrigerator compartment 3, and adapted to act in said compartment as a heat absorber and, therefore, as an auxiliary cooling medium for said compartment. The bottom of the pan 12 is pitched at a general forward and upward inclination, adapting it to accumulate and hold a quantity of water before overflowing into the pans 14, which in turn are pitched at a general forward and downward inclination following the inclination of the inner bottom face of the show-case on which they rest. Each of the pans 14, which has its bottom transversely corrugated to accumulate and hold a portion of the brine water flowing therethrough, is open at its top and is covered and protected by a openwork wire screen 15, and these pans are adapted to overflow at their forward ends for discharge into a drain basin 16 provided with a drain tube 17 on which is mounted a removable

trap 18 in the form of a tube, bent to substantially U-shape, as seen more clearly in Figure 2. This construction permits of the trap being readily removed in order that the basin 16 and pipe 17 may be properly 70 and conveniently cleaned.

Attached at its upper edge to the front wall of the container at a point below the uppermost flues or passages 9, is an insulated shield or baffle 19, preferably consisting of 75 outer metal plates having between them, an insulated asbestos filling. This shield extends from its point of attachment, outwardly away from the container at a suitable inclination downwardly to provide for 80 the free passage of air outward through the flues 8 immediately behind said baffle and also for the free passage of air upward between said baffle and the adjacent wall of the casing 1 into the uppermost flues or 85 passages 9.

Abutting at its rear end, against the baffle 9, at a point suitably below the upper wall of the casing 1, and extending longitudinally through the compartment 3 in spaced 90 parallel relation with said wall, is a plate 20 of insulated construction like the baffle 19, constituting an insulated shield lying beneath the top of the compartment 3. This plate which is of angular cross section and 95 inclines from its side edges inward and downward to its medial bottom line, cooperates with the top wall of the casing to form an air passage or duct 21 running longitudinally through the compartment 3 100 and having side inlets 22 and a forward end inlet 23 formed, respectively, by suitably spacing the side edges of the plate from the adjacent walls of the casing and by terminating the plate short of the forward end of the casing. The duct thus formed, operates to convey the air circulating through the refrigerator compartment, or show-case proper, in its return path to the refrigerating compartment and more 110 particularly to the passages 9 leading through the refrigerant, as indicated by the arrows in Figure 2, it being noted in this connection that the inclined side walls of the show-case act to direct the air upward 115 and through the inlets 22 into the duct 21, while the inner surface of the casing at its forward end is suitably curved at the points 24 and 25, for directing the outflowing current of air upward along the forward end 120 wall of the casing and back into the forward end of the duct through the inlet opening 23.

Mounted on suitable supports in the compartment 3, is a pair of vertically spaced 125 latticed shelves 26 and 27 of which the lower shelf 26 is disposed immediately above and in spaced relation to the screen 15, which covers the pan 14, while the shelf 27, which together with the shelf 26, afford ample 130

accommodation for the goods to be displayed, is disposed about centrally between the shelf 26 and shield 20.

In practice the container 7, having been 5 filled with the refrigerant, such as described, which may be introduced thereinto by opening the door 4, and the goods to be preserved and displayed having been properly arranged on the shelves 26 and 27 within the 10 compartment 3 to which the goods is introduced through the doors 6, the doors are all properly closed and refrigeration begins. The warm air within the casing, naturally 15 rises and is directed in the manner heretofore explained, into the passageway 21 through which it travels rearwardly toward the refrigerative body and is directed by the baffle 19, upward between the walls of the casing and container, into the uppermost 20 tubes or passages 9. The air entering these passages 9 flows through the refrigerative body to the rear space or chamber 10, and thence backwards through the refrigerative body by way of the passages 8 to the compartment 3. It is obvious that the air in 25 flowing back and forth through the refrigerative body or unit, becomes highly refrigerated and rarified in the manner fully explained in the above noted patent, to which 30 reference may be had for a more detailed description on this point. The warm air in passing from the duct 20 to the flues 9 is, because of the upward inclination of the latter, caused to travel more readily than heretofore, while the refrigerated air returned 35 to the compartment 3 through the flues 8 is, because of the downward inclination and tapered formation of the latter, caused to travel more readily than heretofore, and is 40 directed downward and in a path along and immediately above the pan 14, which acts as an auxiliary cooling medium for preserving the highly chilled condition of the air. The baffle 19 serves not only to direct the air from 45 the upper flues 8 downward, but also to set up an insulation between the cold air and the warm air which is being returned to the refrigerant, thus to prevent chilling of the warm air by direct contact and preventing 50 the formation of an eddy current at the rear end of the passage 21, while the curvature given to the inner face of the refrigerator compartment at the points 24 and 25, serves not only to direct the current of air as heretofore explained, but also to eliminate dead 55 air spaces and the formation of eddy currents at these points.

It will be recognized as an obvious condition in the operation of a refrigerator of this 60 type, that the opening of the doors 6 for removing from the compartment 3, the goods being sold or dispensed, admits warm air to said compartment at frequent intervals, and that in order to preserve the necessary 65 low temperature, this air must be quickly carried to the refrigerant to be chilled thereby. This is accomplished through the provision of a shield 20 which not only prevents the goods being piled upon the shelf 27 in a manner to block the circulation of air, but 70 also operates as a duct which immediately receives the warm air admitted through the door 6 and carries this air to the compartment 2, for refrigeration, it being noted that such air, as may be admitted by opening one 75 of the doors 6, will, when said door is closed, be thrown against the opposite side wall of the compartment and because of the inclination of said wall, be thrown upward into the space or duct 21 through the inlet 22, 80 where it will be taken up by the current of air flowing through said space and carried to the refrigerant in the manner heretofore explained.

The circulation of the air in a show case 85 refrigerator of the type described is of special utility where the doors are at the side and where panels are arranged at the side or sides. This arrangement avoids loss; for when the doors are opened, the outside air 90 will not rush in as would be the case if the doors were at the end or at the top, in view of the fact that the doors are not in the direct path of the refrigerating current of cold air. Moreover, this construction prevents moisture from accumulating on the 95 glass panels so that these glass panels will not become clouded, thereby maintaining a clear vision of the articles inside of the refrigerator, which is necessary in show case 100 constructions. The inclined walls are of special utility in a construction where the refrigerating current is in a path along the bottom and along the top as this not only prevents the formation of air pockets in the 105 corners thereby retarding the circulation, but also concentrates the returning warm air in the narrow duct forming only a small part of the total show case volume.

From the foregoing it is apparent that the device accomplishes the stated objects of the invention, among which may be mentioned chiefly, the directing of the outflowing current of air downward toward the bottom of the compartment 3 for travel beneath the goods on the shelves and along and in contact with the auxiliary cooling medium 14; the rapid collecting of the warm air and its quick return to the refrigerating compartment, and the induction of a ready flowing 110 of the air in the passages 8 and 9 through the refrigerative body. It is to be understood that in attaining these ends, various minor changes may be made in the details herein set forth without departing from the 115 spirit or scope of the invention.

Having thus described the invention, what is claimed is:

1. A counter refrigerator comprising a casing having a refrigerator compartment 130

and a compartment adapted to receive a refrigerant, means for causing a current of air to circulate through said refrigerator compartment outward from said refrigerator 5 and in a return path thereto, an open-ended duct provided at the top of the refrigerator compartment adapted to receive and convey the air in its said return path, the duct having lateral inlets, and a side door in said 10 refrigerator compartment positioned so as to be out of the path of said current of air.

2. A counter refrigerator comprising a casing having a refrigerator compartment and a compartment adapted to receive a refrigerant, means for causing a current of air to circulate through said refrigerator compartment outward from said refrigerator and in a return path thereto, and an open-ended duct provided at the top of the refrigerator 15 compartment adapted to receive and convey the air in its said return path, the duct having lateral inlets and the said compartment having upwardly and inwardly sloping side walls.

25 3. A counter refrigerator comprising a casing having a refrigerator compartment provided with upwardly and inwardly sloping side walls, means for refrigerating said compartment, means for causing a current 30 of air to circulate through said compartment, the path of the warmer air being along the top thereof, and a shield beneath the top of said compartment opening toward the sides and one end thereof.

35 4. A refrigerator comprising an elongated show-case provided with transparent panels at the side thereof and constituting a refrigerator compartment, a refrigerant container at one end of said compartment, a 40 waste pan extending from said container along the bottom of said compartment, adapting the waste from the refrigerant to collect and flow along the bottom of, and through, said compartment in order to act as an auxiliary cooling medium therefor, and means for causing a current of air to circulate through said show-case in a path along and immediately above and in contact with the auxiliary cooling medium.

50 5. A refrigerator comprising a show-case provided with transparent panels at the side thereof and constituting a refrigerator compartment, a refrigerant container at one end of said compartment, means adapting 55 the waste from the refrigerant to flow along the bottom of, and through, said compartment as an auxiliary cooling medium therefor, means for causing a current of air to circulate through said show-case in a path along and immediately above the auxiliary 60 cooling medium and in a return path along the top of the show-case, and a shield beneath and spaced from the top of the show-case.

65 6. A refrigerator comprising a show-case

provided with transparent panels, a refrigerating unit mounted at one end of the show-case and adapted to receive a refrigerant, and means adapting the waste from the refrigerant to flow through the show-case 70 along the bottom thereof, as an auxiliary cooling medium therefor, the said refrigerating unit having passages therethrough, said passages being pitched at an inclination to cause a current of air to circulate through 75 said unit and show-case in a path along and immediately above the auxiliary cooling medium.

7. A refrigerator comprising an elongated show-case provided with transparent panels 80 at the side thereof, a refrigerating unit at one end thereof adapted to receive a refrigerant, an overflow pan extending along the bottom of the show-case and adapted to be fed by waste from the refrigerant and to 85 form an auxiliary cooling medium, and means for causing a current of air to circulate through the show-case in a path along and immediately above said pan and in contact with the cooling medium. 90

8. A refrigerator comprising an elongated show-case having transparent panels at the side thereof, a refrigerating unit mounted at one end of the show-case, said unit having 95 passages therethrough opening toward the show-case, means adapting the waste from said unit to collect and flow along the bottom, and through, the show-case, and a shield lying beneath and spaced from the top of the show-case adapted to direct the 100 air currents therein.

9. A refrigerator comprising an elongated show-case having transparent panels at the side thereof, a refrigerating unit mounted at one end of the show-case, said unit having 105 passages therethrough opening toward the show-case, an overflow pan extending along the bottom of the show-case for carrying off the waste from the said unit, and a shield lying beneath and spaced from the top of 110 the show-case adapted to direct the air currents therein.

10. A counter refrigerator comprising an elongated show-case having upwardly and inwardly inclined side walls and provided 115 with transparent panels, and a refrigerating unit adapted to receive a freezing mixture and mounted at one end of said show-case, said unit having passages constructed and arranged to permit a circulation of air 120 therethrough and along the back thereof, and said unit being adapted and positioned to cause a current of air to circulate in a path from the bottom of said unit along the bottom of the show-case and in a return 125 path along the top of the show-case into the top of said unit.

11. A counter refrigerator comprising an elongated show-case provided with transparent panels at the side thereof, a refrig- 130

- erating unit adapted to receive a freezing mixture and mounted at one end of said show-case, said unit having passages constructed and arranged to permit a circulation of air therethrough and along the back thereof, and said unit being adapted and positioned to cause a current of air to circulate in a path from the bottom of said unit along the bottom of the show-case and 10 in a return path along the top of the show-case into the top of said unit, and an open top overflow pan arranged along the bottom of the show-case and adapted to receive the brine from said unit.
- 15 12. A counter refrigerator comprising an elongated show-case having upwardly and inwardly inclined side walls and provided with transparent panels, and a refrigerating unit adapted to receive a freezing mixture and mounted at one end of said show-case, said unit having passages constructed and arranged to permit a circulation of air therethrough and along the back thereof, and said unit being adapted and positioned 20 to cause a current of air to circulate along the bottom of said show-case outward from said unit and in a return path along the top of said show-case to said unit.
- 30 13. A counter refrigerator comprising an elongated show-case having upwardly and inwardly inclined side walls and provided with transparent panels, a refrigerating unit at one end of said show-case, and means for causing a current of air to circulate from said unit along said show-case, the path of the cold air being along the bottom thereof and the path of the warmer air being along the top thereof.
- 40 14. A counter refrigerator comprising, an elongated show-case having upwardly and inwardly inclined side walls and provided with transparent panels, a refrigerating unit at one end of said show case, said unit having passages constructed and arranged
- to permit a circulation of air therethrough 45 and along the back thereof, and said unit being adapted and positioned to cause a current of air to circulate in a path from the bottom of said unit along the bottom of the show-case and in a return path along the 50 top of the show case into the top of said unit, and a pan extending along the bottom of the show-case beyond said unit and adapted to receive the brine from said unit.
15. A counter refrigerator comprising, an 55 elongated show-case provided with transparent panels, a refrigerating unit mounted at one end of said show-case, said unit having passages constructed and arranged to permit circulation of air therethrough and 60 along the back thereof, an auxiliary refrigerating element extending along the bottom of said show-case beyond said unit, and a latticed provision shelf immediately above said element, whereby a current of air is 65 caused to circulate in a path from the bottom of said unit along the bottom of the show-case and in a return path along the top of the show-case into the top of said unit. 70
16. A counter refrigerator comprising, an elongated show-case provided with transparent panels, a refrigerating unit mounted at one end of said show-case, said unit having passages constructed and arranged to 75 permit circulation of air therethrough and along the back thereof, an auxiliary refrigerating element extending along the bottom of said show-case beyond said unit, and latticed provision shelves above said element, whereby a current of air is caused 80 to circulate in a path from the bottom of said unit along the bottom of the show-case and in a return path along the top of the show-case into the top of said unit. 85

In testimony whereof I affix my signature this 27th day of July, 1916.

JOHN SCHULDE.
